FIG. 1 is a perspective elevational view taken from the top of a combined sprayer tank cap and pressure relief valve showing our new design;

FIG. 2 is a top, front and right side perspective view thereof;

FIG. 3 is a right, front and top perspective view of the pressure relief valve, shown separately for ease of illustration;

FIG. 4 is a left, front and top perspective view thereof;

FIG. 5 is a right, front and bottom perspective view thereof;

FIG. 6 is a left, front and bottom perspective view thereof;

FIG. 7 is a top view thereof;

FIG. 8 is a front elevation thereof;

FIG. 9 is a right side elevational view thereof; and,

FIG. 10 is a left side elevational view thereof.
